UNITED STATES PATENT OFFICE.

MILTON H. BALLARD, OF LYNN, MASSACHUSETTS, ASSIGNOR TO TRIPP
FRUIT WRAPPING MACHINE COMPANY, OF SAN FRANCISCO, CALI-
FORNIA, A CORPORATION OF MAINE.

WRAPPING-MACHINE.

No. 851,214.

Specification of Letters Patent.

Patented April 23, 1907.

Application filed April 20, 1906. Serial No. 312,749.

To all whom it may concern:

Be it known that I, MILTON H. BALLARD, of Lynn, county of Essex, State of Massachusetts, have invented an Improvement in Wrapping-Machines, of which the following description, in connection with the accompanying drawings, is a specification, like characters on the drawings representing like parts.

This invention relates to wrapping machines for wrapping oranges and other articles, such for instance as shown in Letters Patent # 812,912, dated February 20, 1906, and has for its object to provide means for operating the stop-motion of the machine adapted to be controlled by the paper wrinkling between the feeding device and the cutting-device, and also by the web of paper breaking between the paper-carrying roll and the feeding-device. In the machine shown in said patent the web of paper taken from the paper-carrying roll is fed forward by suitable feeding-devices to a cutting-device, and the latter operates to sever the web of paper, and the severed end portion serves as and constitutes the wrapper which is to be used in wrapping the orange or other article.

It sometimes happens that when the paper is fed forward to the cutting-device it does not pass freely between the cooperating members of said device, and in such event it wrinkles between the feeding-device and cutting-device, and a wrapper is not produced. It also sometimes happens that when the web of paper breaks at some point between the paper-carrying roll and the feeding-device, and in such event no wrapper is produced, and in either case it is very desirable to instantly stop the machine.

My present invention comprehends the provision of an electro-magnet for operating the stop-motion to stop the machine, and means for operating the circuit of said electro-magnet adapted to be controlled by the paper wrinkling between the feeding-device and cutting-device, and means for also operating the circuit of said electro-magnet adapted to be operated by the breaking of the web of paper between the paper-carrying roll and feeding-device.

Figure 1 shows in side elevation a sufficient portion of a wrapping-machine to illustrate my invention, having a stop-motion and means embodying my invention for operating

it. Fig. 2 is an enlarged detail of the stop-motion to be referred to. Fig. 3 is an enlarged detail of an electro-magnet and a portion of the stop-motion to be referred to. Fig. 4 is an enlarged cross sectional detail showing the feeding-device and cutting-device and controlling-device for the circuit of the electro-magnet employed for operating the stop-motion, the web of paper being shown as properly fed forward by the feeding-device to the cutting-device. Fig. 5 is a sectional detail, similar to Fig. 4, the web of paper being broken between the paper-carrying roll and the feeding-device. Fig. 6 is a detail, similar to Fig. 4, the paper being improperly fed to the cutting-device and consequently wrinkled between said devices. Fig. 7 is a plan view of the feeding-device and cutting-device and controlling-devices shown in Fig. 4. Fig. 8 is a sectional detail of the support for the stationary member of the circuit operating device. Fig. 9 is a side view of the aforesaid support.

The stop-motion of the machine is substantially the same as shown in Letters Patent # 812,912, aforesaid, and consists of a lever 217, pivoted to the frame, to the extremity 80 of which is loosely connected an upright bar 218, bearing at its lower end a wedge-block 219, which projects laterally therefrom and which is moved into and out of engagement with one end of a short horizontal slide-bar 220, having a shoe or end piece 221 at its opposite end which is formed or provided with a curved engaging-face. The short bar 220 slides in a stationary bearing provided for it. The sliding bar 220 is moved forward in a direction toward the loose driving-wheel 222 by a spring 224, and is held against rearward motion by the wedge-block when said wedge block is brought into engagement with the rear end thereof for the purpose of stopping the machine, otherwise it is not held against rearward motion. The sliding-bar serves as a yielding restraining-device for the clutch-mechanism, and the wedge block serves as the controlling-device for the stop-motion.

The clutch-mechanism consists of a clutch arm 223 pivoted at 224 to a hub secured to the main shaft f^5 , and said clutch-arm projects in a radial direction and bears a shoe 226 near its extremity which is adapted to engage the inner face of the rim of the loose

driving-wheel, and said clutch-arm is raised on its pivot by a spring 227 which is supported on an arm 228 fixed to the hub on the shaft to thereby hold the shoe 226 firmly in engagement with the rim of the loose driving-wheel, so that the clutch-mechanism and shaft bearing it will be turned, but whenever the clutch-arm is pressed down against the action of said spring 227, the shoe 226 will be moved out of engagement with said rim and the shaft f^5 will remain at rest. The clutch-arm 223 extends beyond the rim of the driving-wheel into position to engage the shoe or end-piece 221 of the yielding restraining-device, and when said restraining-device is free to yield the arm will engage but will freely pass by it and the main shaft will revolve, but when said restraining-device is positively held against rearward motion, the end of the clutch-arm will engage the outer face of the shoe 221, the momentum of the shaft f^5 and part connected thereto will be suddenly absorbed, and the shaft will cease turning. The position of the wedge-block 219 determines whether the restraining-device shall yield, or shall not, and the position of the wedge-block is determined by the position of the arm 218 bearing it, and of the arm 217 to which said arm 218 is connected. When the arm 217 is raised the wedge-block will be likewise raised and will engage the yielding restraining-device and hold it and check further movement of the clutch-arm, and when said arm 217 is permitted or caused to fall the wedge-block will be removed from engagement with the restraining-device and the clutch-arm will be permitted to pass by it.

A cam 250 is pivoted to the frame which has a hand-piece 251 for turning it, which latter serves as the starting-lever, and said cam is located close to the wedge-block so that the wedge-block will occupy a position between said cam and the rear end of the sliding-bar, and the cam thus supports against lateral movement and guides the lower end of the vertical bar 218, and said cam has a projection which is adapted to enter a slot 252 formed at the lower end of the bar 218, which is made long enough to provide for an independent movement of said bar, and when said cam is turned, as by lifting the lever 251, the bar 218 will be drawn down and the yielding restraining-device will be disengaged and the clutch-arm relieved to thereby start the machine. When the machine is thus started the cam will be immediately returned to its normal position by the weight of the hand-lever, and the wedge-block will remain in its lowermost position by gravity until positively raised. When the arm 217 is raised to lift the wedge-block, the latter will resume its position at the rear end of the sliding-bar, and as soon as the end piece 221 on said bar is engaged by the clutch arm, said bar will be moved rearwardly, and

the wedge-block will be held firmly between the bar and the cam, and will remain in such position until positively moved downward by lifting the hand-lever and turning the cam and drawing down the bar. Thus it will be seen that while the tendency is for the wedge-block to fall by gravity it will be positively held in its elevated position by the action of the clutch-arm, except when positively moved downward by the cam. An electro-magnet m is provided for lifting said arm 217 to lift the wedge-block and stop the machine, and said electro-magnet is included in a circuit m' containing a battery m^2 , or other source of energy, and also containing one or more circuit operating devices adapted to close the circuit and thereby energize the electro-magnet and lift the arm 217.

One of the circuit operating devices may consist of an ordinary press-button m^3 , adapted to be operated by hand, and located at any part of the machine. The other circuit operating device is herein shown as adapted to be operated by two different means, namely, by the paper wrinkling between the feeding-device and the cutting-device, and by the web of paper breaking between the paper-carrying-roll and the feeding-device.

m^3 represents the paper-carrying roll;

41 and 42 represent the feeding-rolls, 95 which are operated intermittently to feed forward the paper from the paper-carrying-roll to the cutting-device, and which, therefore, constitute the feeding-device for the paper; and 306 represents a knife, which is herein shown as a vertically reciprocating blade. Between the bite of the feeding-rolls 41, 42, and the cutting-device a flat bed 302 is provided over which the paper is fed. The upper feed-roll 41 is held pressed down 105 by a pressure-block 50, bearing upon it at a point intermediate its length, and said block 50 is set in a suitable frame and is thrust down by a spring 51, see Fig. 8. The block 50 has a stem passing up through the top of the frame to the upper end of which a cap 52 is secured which may be engaged by the fingers to lift the pressure-block and disengage it from the feeding-roll. The stem has a laterally projecting pin 53, which, when the pressure-block is raised passes through a slot in the top of the frame, and then by turning said stem said pin may be brought into position above the top of the frame to engage therewith when the stem is released and thereby hold the pressure-block elevated. The frame bearing the pressure-block is pivoted at 54 to the machine frame, and may be swung on its pivot to thereby permit the upper feed-roll to be removed from its bearings. The frame has a laterally extended arm 55 at the extremity of which a contact-screw 56 is secured, which forms the stationary member of the circuit-operating-device, one of the circuit-wires being attached to said 130

screw. This member is stationarily supported in a predetermined position by the frame when the pressure-block, borne by said frame, is in engagement with the feed-roll, said pressure-block, therefore, serving as a locking device for holding the frame in such position. An arm 60 is pivoted at 61 which is curved in the direction of its length and extends over the upper feed-roll and terminates at a point 5 between the feed-roll and the knife, a short distance above the flat bed over which the paper is fed. This arm falls by gravity until it strikes a reduced portion of the upper feed-roll or some other fixed stop which limits its 10 downward movement. The paper is fed forward by the feed-rolls to the cutting-device beneath the extremity of said arm, but if the paper should not be correctly fed forward it will wrinkle between the feed-rolls and cutting-device, as shown in Fig. 6, and the wrinkled portion thereof will engage the end of the arm 60 and lift it. The arm bears a contact 62 which is adapted to close upon the end of the contact-screw 56, to thereby close 15 the circuit of the electro-magnet *m*, and one of the circuit wires is connected to the pivot-shaft of said arm to provide a path for the current. Thus if the paper should not be fed correctly to the cutting-device and consequently 20 should wrinkle between the feed-rolls and the cutting-device, the arm 60, which serves as the circuit-operating-lever, will be lifted, and the contacts 62, 56 closed, to thereby close the circuit of the electro-magnet *m*, which, upon being energized will 25 operate the stop motion and stop the machine. Also pivoted at 61 is an arm 70 which extends rearwardly, and bears at its extremity a flat bar 71, of any suitable length, which 30 rests by gravity upon the web of paper back of the feed-rolls, that is to say, between the feed-rolls and the paper-carrying-rolls, and is held in elevated position by the web of paper 35 as it is being fed forward by the feed-rolls, but if said web of paper should break the arm 70 will fall by gravity, being no longer supported in elevated position. The arm 70 has a laterally extended pin 72 which occupies a 40 position above a pin 73 projecting rearwardly from the arm 60, and when said arm 70 falls by gravity by reason of the web of paper breaking, said pin 72 will engage the pin 73 and lift the arm 60 on its pivot to thereby cause its contact point 62 to engage the contact 45 screw 56 and close the circuit of the electro-magnet *m*. Thus it will be seen that if the web of paper breaks between the paper-carrying-roll and the feeding-device, the arm 70, which serves as a circuit-operating-lever, will fall by gravity and close the circuit 50 of the electro-magnet *m* and thereby operate the stop-motion to stop the machine.

By the construction thus shown and described, a single circuit-operating-device may 55 be employed which is adapted to be operated

by two independent operating levers; but so far as my invention is concerned I do not desire to limit it to the employment of a single circuit-operating-device, or to the employment of the particular construction and arrangement of the parts herein shown, as it is obvious that they may be modified in many respects and the same results accomplished. Neither do I desire to limit my invention to the employment of the particular form of 70 stop-motion herein shown, as it is obvious that other forms of stop-motion may be employed without departing from the spirit and scope of my invention, the particular form herein described, being shown merely for the 75 sake of illustrating one practical embodiment of my invention.

Having thus described my invention, what I claim as new and desire to secure by Letters Patent is:—

1. In a wrapping machine, the combination of a paper-feeding-device, a paper-cutting-device to which the paper is fed by the feeding-device, a stop-motion for the machine, an electro-magnet for operating it, a 90 circuit for said electro-magnet, a circuit operating lever therefor, located between the feeding-device and cutting-device, and adapted to be operated by the paper wrinkling between said devices, substantially as described.

2. In a wrapping machine, the combination of a paper-feeding-device, a paper-cutting-device to which the paper is fed by the feeding-device, a stop-motion for the machine, an electro-magnet for operating it, a 100 circuit for said electro-magnet, a circuit operating-lever therefor which overlies the paper between the feeding-device and cutting-device and is adapted to be engaged and 105 lifted by the paper wrinkling between said devices, substantially as described.

3. In a wrapping machine, the combination of a paper-feeding-device, a paper-cutting-device to which the paper is fed by the feeding-device, a stop-motion for the machine, an electro-magnet for operating it, a circuit for said electro-magnet, an operating-device for said circuit comprising a stationarily supported member and a movable 115 member, the latter being constructed and arranged to overlie the paper between the feeding-device and the cutting-device, and adapted to be engaged and lifted by the paper wrinkling between said devices, substantially 120 as described.

4. In a wrapping machine, the combination of a paper-feeding-device, a paper-cutting-device to which the paper is fed by the feeding-device, a stop-motion for the machine, an electro-magnet for operating it, a 125 circuit for said electro-magnet, an operating-device for said circuit comprising a stationarily supported member, and a pivoted arm bearing a contact which serves as the mov- 130

able member, said arm occupying a position between the feeding-device and cutting-device and terminating close to the paper which is fed forward by the feeding-device to the 5 cutting-device, to be engaged and lifted by said paper wrinkling between said devices, substantially as described.

5. In a wrapping machine, the combination of a paper-feeding-device, a paper-cutting-device to which the paper is fed by the feeding-device, a stop-motion for the machine, an electro-magnet for operating it, a circuit for said electro-magnet, a circuit-operating-device comprising a stationary member and a movable member, the latter overlying the paper between the feeding-device and the cutting-device and adapted to be engaged and lifted by the paper wrinkling between said devices, a movable frame bearing 10 the stationary member and a locking-device for holding said frame in a position for the two members of the circuit-operating-device to coöperate, substantially as described.

6. In a wrapping machine, the combination of a paper-feeding-device, a paper-cutting-device to which the paper is fed by the feeding-device, a stop-motion for the machine, an electro-magnet for operating it, a circuit for said electromagnet, a circuit-operating-device comprising a stationary member and a movable member, the latter overlying the paper between the feeding-device and the cutting-device, and adapted to be engaged and lifted by the paper wrinkling 25 between said devices, a movable frame bearing the stationary member, and a locking-device, engaging the upper feed-roll, for holding said frame in proper position for the two members of the circuit-operating-device to 30 cooperate, substantially as described.

7. In a wrapping machine, the combination of a stop-motion for the machine, a starting lever for operating said stop motion to start the machine, an electro-magnet for 45 operating said stop motion to stop the machine and to bring one of the cooperating members thereof into frictional engagement with the starting lever, by which it is held and an operating device for the circuit of said 50 electro-magnet which is controlled by the paper, substantially as described.

8. In a wrapping machine, the combination of a stop-motion for the machine, a starting lever for operating said stop motion to start the machine, an electro-magnet for 55 operating said stop motion to stop the machine and to bring one of the cooperating members thereof into position to be engaged by said starting lever and an operating device for the circuit of said electro-magnet which is controlled by the paper, substantially as described.

9. In a wrapping machine, the combination of a stop-motion for the machine having 60 a controlling-device, a starting lever for oper-

ating said controlling-device to start the machine, an electro-magnet for operating said controlling-device to stop the machine and to move it into position to be engaged by the starting lever and an operating-device for the 70 circuit of said electro-magnet which is controlled by the paper, substantially as described.

10. In a wrapping machine, the combination of a stop-motion for the machine having 75 a controlling-device, a starting lever for operating said controlling-device to start the machine, an electro-magnet for operating said controlling-device to stop the machine and to move it into position to be engaged by the 80 starting lever, a circuit operating-device for the circuit of said electro-magnet, and an operating-device for said circuit operating-device adapted to be lifted by the paper wrinkling, substantially as described.

85 11. In a wrapping machine, the combination of a stop-motion for the machine having a controlling-device, a starting lever for operating said controlling-device to start the machine, an electro-magnet for operating 90 said controlling-device to stop the machine and to move it into position to be engaged by the starting lever, a circuit operating-device for the circuit of said electro-magnet and an operating device for said circuit operating-device which rests upon the web of 95 paper and is adapted to fall by gravity when the web of paper breaks, substantially as described.

100 12. In a wrapping machine, the combination of a stop-motion for the machine having a controlling-device, a starting lever for operating said controlling-device to start the machine, an electro-magnet for operating said 105 controlling-device to stop the machine and to move it into position to be engaged by the starting lever, a circuit operating-device for the circuit of said electro-magnet, an operating-device for said circuit operating-device adapted to be lifted by the paper wrinkling 110 and another operating-device for said circuit operating device which rests upon the web of paper and is adapted to fall by gravity when the web of paper breaks, substantially as described.

115 13. In a wrapping machine, the combination of a paper-carrying-roll, a paper-feeding-device, a paper-cutting-device, a stop-motion for the machine, an electro-magnet for operating said stop-motion to stop the machine, a circuit-operating-device for the circuit to said electro-magnet, which overlies 120 the paper between the feeding-device and cutting-device and is adapted to be engaged and lifted by the paper wrinkling between 125 said devices, and an operating-lever for circuit-operating device, which rests by gravity upon the web of paper between the paper-carrying-roll and the feeding-device and is adapted to fall by gravity when the web of 130

paper breaks to thereby operate said circuit operating-device, substantially as described.

14. In a wrapping machine, the combination of a paper-carrying-roll, a paper-feeding-device, a paper-cutting-device, a stop-motion for the machine, a starting-lever for operating said stop-motion to start the machine, an electro-magnet for operating said stop-motion to stop the machine, a circuit operating-device for the circuit of said electro-magnet, which overlies the paper between the feeding-device and cutting-device and is adapted to be engaged and lifted by the paper wrinkling between said device, and

an operating-lever for lifting the aforesaid circuit-operating device which rests by gravity upon the web of paper between the paper-carrying roll and the feeding-device and is adapted to fall by gravity when the web of paper breaks to thereby operate said circuit operating-device, substantially as described.

In testimony whereof I have signed my name to this specification, in the presence of two subscribing witnesses.

MILTON H. BALLARD.
